UNITED STATES PATENT OFFICE.

LOUIS ERNST, OF READING, OHIO.

GAME.

SPECIFICATION forming part of Letters Patent No. 696,862, dated April 1, 1902.

Application filed June 29, 1901. Serial No. 66,569. (No model.)

To all whom it may concern:

Be it known that I, LOUIS ERNST, a citizen of the United States, residing at Reading, in the county of Hamilton and State of Ohio, have 5 invented new and useful Improvements in Games, of which the following is a specification.

This invention relates to games, the object in view being to provide a game-board with 10 movable objects thereon and provided with tunnels or raceways arranged in parallel order and adapted to form guides for the movable objects, the device being movably supported upon a centrally-located rocker-post by means 15 of which the operator is enabled to manipulate the board by tilting the same in various directions, thereby causing the movable objects, which are usually in the form of balls or marbles, to traverse the surface of the board 20 in different directions.

The object in playing the game is to cause the different balls or marbles, which are differently designated, to traverse different tunnels or raceways, the game being won by the 25 person who exercises the greatest skill and causes the balls or marbles to traverse their respective tunnels or raceways.

With the above general objects in view the invention consists in a game embodying certain novel features of construction and arrangement of parts hereinafter fully described, illustrated, and claimed.

In the accompanying drawings, Figure 1 is 30 a plan view of a game-board constructed in accordance with the present invention. Fig. 2 is a vertical cross-section through the same, taken on the line 2 2 of Fig. 1. Fig. 3 is also a vertical cross-section taken at right angles to Fig. 2 and on the line 3 3 of Fig. 1.

Like numerals of reference designate corresponding parts in the several views.

The game contemplated in this invention comprises, essentially, a base or board 10, representing the field of operation, the said base 45 or board being surrounded by an upstanding rim 11, which extends around three sides of the board and which is connected at the front by means of a fender or strip 12, which forms the outer wall of a terminal "pen" 13.

In forming the base or board 10 it is usually preferable to construct the same in two pieces, 50 14 designating the lower board or bottom

proper, and 15 a thicker board, which is mounted upon and supported by the bottom 14 and which is of sufficient thickness to allow for 55 the formation therein of a series of parallel bores 16, forming tunnels or raceways for a corresponding series of rolling objects, preferably in the form of balls or marbles, as indicated at 17.

The board 15 terminates short of the fender or strip 12, as shown in Figs. 1 and 3, so as to establish the terminal pen 13, and the rolling elements are confined upon the upper surface of the upper board 15 by means of the surrounding rim 11 and a shallow guard 18 in the form of a strip, such as a piece of molding, extending across the front edge of the upper board 15, as clearly illustrated in Fig. 3. The strip 18 is, however, sufficiently low to 70 require the operator to exercise considerable skill in order to prevent the rolling elements from jumping over such guard and finding their way accidentally into the terminal pen 13.

The inner ends of the raceways 16 are flared to form bell-shaped openings or mouths 19, having elliptical entrances parallel with the tunnels or raceways to facilitate the dropping of the rolling elements therein.

The rolling elements 17 are primarily deposited within an initial inclosure 20, arranged in one of the upper corners of the board and defined by the rim 11 and a curved strip or fence 21, the initial inclosure being 85 sufficiently large to contain all of the rolling elements, any desired number of which may be employed, but which should correspond in number with the number of openings 19 and tunnels or raceways 16, extending upwardly 90 through the surface of the board.

The board has represented thereon opposite each of the openings 19 the name of some country, and it is also desirable in some cases to correspondingly name the balls or marbles 17 by printing or otherwise representing thereon the names of such countries. One of the balls or marbles 17 is preferably made larger than the rest and is printed to represent the United States.

In order to enable the operator to tilt and vary the angle of the base or board 10, such board is provided about centrally with a rocker-post 22, having a rounded lower sur-

face 23, adapted to rest upon a table or similar support, and in order to limit the rocking or tilting movement of the base a stop 24 in the form of a depending strip is extended 5 along the rear side of the base, as illustrated in Fig. 3, said stop being adapted to strike against the table or other support in a manner that will be readily understood.

In playing the game the several operators 10 take their turns or innings, and each operator places one or more of the balls 17 upon the surface of the board and by tilting or rocking the board in various directions endeavors to cause such balls to enter their respective openings 19 and traverse the tunnels or raceways 16, so as to be delivered finally 15 into the terminal pen 13. During this operation the larger ball, representing the United States, is caused to traverse the surface of 20 the board in company with the other ball or balls, so as to direct such balls into their respective openings by impinging against the same, the large ball being of sufficient size to prevent it from falling into any of the openings or mouths 19 and passing through the 25 tunnels or raceways 16. The game is won by the player who causes the largest number of balls to enter their respective openings or mouths and pass through the tunnels or race- 30 ways into the terminal pen 13.

It will be apparent that any number of openings or mouths and tunnels or raceways, as well as any number of balls, may be employed according to the desire or taste of the manufacturer. These and other changes in the 35 form, proportion, and the minor details of construction may be resorted to without de-

parting from the principle or sacrificing any of the advantages of the invention.

Having thus described the invention, what 40 is claimed, and desired to be secured by Letters Patent, is—

1. A game-board comprising a parallel series of tunnels each having a ball-opening extending through different parts of the surface 45 of the board, a pen into which the balls are discharged, a rocker-post for facilitating the manipulation of the board and a depending strip adapted to provide a stop at the rear side of the board.

2. The herein-described game apparatus comprising a game-board, an upstanding surrounding rim therefor, and parallel strips or guards forming an elongated terminal pen at one side of the board, the board being provided in its upper surface with openings communicating with raceways leading from such openings to the terminal pen, an initial enclosure located opposite the terminal pen, rolling elements adapted to traverse the surface of the board and to enter said openings and pass through the raceways into the terminal pen, a fulcrum post or rocker extending downward from the bottom of the board, and a stop extending downward from one 60 side of the board for the purpose of limiting the rocking movement of such board.

In testimony whereof I affix my signature in presence of two witnesses.

LOUIS ERNST.
